DIVIDING UNIT FOR AN OPEN TOP REFRIGERATED DISPLAY CASE

Carson J. Morris, Austin, Minn., assignor to Geo. A. Hormel & Company, Austin, Minn., a corporation of Delaware

Application December 8, 1953, Serial No. 27,979

Term of patent 14 years

(Cl. D80—1)

Fig. 1 is a perspective view of a dividing unit for an open top refrigerated display case, showing my new design;

Fig. 2 is a side view of the display; and

Fig. 3 is a front view of the same.

I claim:

The ornamental design for a dividing unit for an open top refrigerated display case, substantially as shown.
